UNITED STATES PATENT OFFICE.

SAMUEL EDELSOON, OF NEW YORK, N. Y.

DOOR LOCK.

Application filed September 18, 1923, Serial No. 663,427. Renewed April 19, 1927.

In my Letters Patent No. 1,512,915, dated October 28, 1924, I showed a door lock and the present invention may be applied to a lock of that character although it is not limited in all of its aspects to a lock of that character. Most locks for stores and other places of business as well as homes usually have a cylinder accessible from outside the door so that by means of a key inserted in this cylinder from the outside the lock may be operated; and in addition, there is generally provided a knob or a handle accessible from the inside of the door by means of which the lock may be operated from the inside without a key; and this knob generally operates independently of the cylinder; that is to say, either the knob, or the key inserted in the cylinder may be used to throw the bolts in or out. One of the objects of my invention is to provide a lock having the exterior cylinder and the inner knob but in addition, I provide a cylinder accessible from inside the door together with means by which the knob or handle can be locked in either position. One advantage of this is that where the lock is placed on a door near a glass or where a slight opening can be made sufficient to reach in to the knob, with the present lock, this attempt would not succeed where the knob is locked against operation. So long as a person remains within the building he may use the knob for throwing the lock on or off and then when leaving the building the inner or auxiliary cylinder may be used to lock the knob and then when the operator closes the door from the outside he may use the key inserted in the exterior cylinder for throwing on the lock. When that has been done the door can not be opened either from the outside or inside without the key. My invention therefore relates to a novel device for locking the knob or other hand controlled member.

Another object of my invention is to improve the construction of the bolts and frame plate or keeper shown in my said co-pending application. In the present case the upper and lower bolts which project into the keeper enter into lateral pockets at both the top and bottom of each bolt so that the lock will resist any attempt to open the door with greater strength than the construction shown in my co-pending application.

In the drawings forming part of this application,

Figure 1 is a face view of my improved

lock and keeper looking at the same from the inside of the door,

Figure 2 is a plan view partly in cross section of the lock, the door, and the door frame,

Figure 3 is an elevation of the lock with the front plate and knob removed,

Figure 4 is a sectional view taken on the line 4—4 in Figure 6 which shows the keeper,

Figure 5 is a front elevation of the keeper,

Figure 6 is a side elevation thereof,

Figure 7 is a perspective view of the bolt-throwing member which is operated by the knob, and

Figure 8 is a similar view of the bolt-throwing member which is operated by the exterior cylinder.

The embodiment shown in the drawings includes the casing 1 adapted to contain the various operating parts of the lock and this is closed by a removable cover 2. At one end of the casing there is a wall 3 from which project the two extensions 4, 5 which are larger at their outer ends than their inner ends, producing a dovetail shape. These projections are of U shape in cross section and the upper and lower bolts 6, 7 carried with the sliding bolt plate 8 are adapted to lie partly within these projections 4, 5 when sliding into and out of the casing through the wall 3. In addition, the bolt plate 8 carries a middle bolt 9 which also slides in an aperture in the wall 3.

The keeper or member which is attached to the door frame is shown in Figures 4 to 6 inclusive and it includes a plate 10 which is attached to the door frame by screws as shown in Figure 2. This member also includes a frame 11 disposed at right angles to the plate 10 and it is provided with screw holes 12 for receiving other screws for attaching this member to the door frame.

Looking at the front of this frame there are dovetail openings 13, 14, adapted to freely receive the projections 4, 5 of the lock as the door 15 swings to the closed position. Part of the openings 13, 14 are defined by projections 16 and behind these projections there are formed upper and lower pockets 17, 18 to receive the upper and lower edges of the bolt member 6; and there are upper and lower pockets 19, 20 to receive the upper and lower edges of the bolt member 7. When the door closes it is understood that the several bolts are retracted within the lock

casing and the projections 4, 5, enter freely into the dovetail openings 13, 14 of the keeper. When the bolts are thrown, the upper bolt 6 will enter the upper and lower pockets 17, 18 and lie behind the projections 16. The lower bolt 7 will enter the upper and lower pockets 19, 20 lying behind the projections 16, and the intermediate bolt 9 will enter the opening 21. The door will 10 then be locked not only against opening by swinging on its hinge but the dovetail connection between the projections 4, 5 and the dovetail sockets 13, 14 prevent the door from being forced edgewise and therefore the lock 15 resists opening in every direction. The advantage in the present construction over that of my co-pending case is the added strength obtained by making both upper and lower pockets 17, 18, 19, 20, for the upper and 20 lower bolts.

The bolt plate 8 is guided to move horizontally by the abutments 22 formed on the inside of the lock casing, and by a post 23 which passes through an aperture 24 in the bolt plate. The bolt plate also has an enlarged opening 25 at one end to form a shoulder 26 against which the bolt-throwing members may engage to throw over the bolts into locking position and there is an abutting 30 edge 27 against which the same members may engage to retract the bolts. There is an arm 28 pivoted on the pin 29 and it is forced downwardly by means of the spring 30. This member has a projection 31 which 35 is adapted to engage on either side of the abutment 23 for holding the bolts in either locked or unlocked position, and it is necessary to swing the member 28 to disengage the projection 31 from the abutment 23 to either 40 lock or unlock the bolts. This member 28 extends to the right and is provided with a lateral finger 32 which is adapted to be actuated by either of the bolt-throwing members for lifting the member 28 to disengage the 45 projection 31 from the abutment 23.

There is a key cylinder 33 set into the door 15 and accessible from the outside of the door to receive the key 34. The cylinder 33 has the usual tongue 35 which enters the 50 rectangular slot 36 in the bolt-throwing member 37 so that when the tongue 35 is turned by means of the key inserted in the cylinder 33 the projection 38 on the bolt-throwing member will engage the member 32 55 to swing the arm 28 and it will also engage the shoulder 26 of the bolt plate in one direction to throw the bolts into locking position, and when moving in the reverse direction it engages the shoulder 27 to retract 60 the bolts. This part of the device corresponds with that shown in my said co-pending application and it forms the ordinary means for locking and unlocking the door from the exterior.

There is a second bolt-throwing member 39 65 shown in Figure 7, which is arranged in alignment with the member 37 and it has two projections or wings 40 extending in opposite directions, one of which acts on the member 32 and on the abutments 26, 27 70 to throw the bolt plate in the same manner and for the same purpose as the member 37 and it is adapted to operate while the latter member remains idle.

There is a handle or knob 42 projecting 75 from the lock casing at the inside of the door and this is adapted to be revolved by hand. It projects through the wall 43 of the lock casing and inside there is fixed to it the bolt throwing member 39. By turning 80 the knob 42 the bolt plate 8 may be moved to the right or left by one of the wings 40 in the same manner that the plate is moved by the member 37.

Within the casing there are guiding abutments 44 which guide the horizontally sliding plate 45 which is provided with locking projections 46 which are adapted to straddle either of the wings 40 on the bolt-throwing member 39 whenever one of these wings lies in the right hand position shown in Figure 3. The sliding plate 45 is provided with rack teeth 47 which are operated by a small pinion wheel 48 movable with one of the members of an ordinary lock cylinder 49. This cylinder 49 is disposed in a compartment 50 formed as an extension of the lock casing and the cylinder is so disposed that the key 51 can be inserted only from the inside of the door. When the key is inserted in this cylinder the pinion 48 may be revolved to the left or right for the purpose of sliding the plate 45 into or out of locking engagement with one of the wings 40 of the bolt-throwing member 39. The lock is always in condition to be operated by a key inserted in the cylinder 33 either to lock or unlock the door from the outside. When the plate 45 is in the right hand position shown in Figure 3 the knob 42 may 100 be operated from the inside to either lock or unlock the door and this will ordinarily be used so long as a person remains within the building. When the occupant is about to leave the building or at any other time it is desired to make the knob inoperative, the key 51 is inserted in the cylinder 49 and turned and this will cause the pinion 48 to move the plate 45 to the left in Figure 3 so that the projections 46 straddle one of the wings 40 and prevent the knob 42 from being turned in either direction. When the lock is thus set the knob 42 can not be operated and therefore the bolts can not be thrown in either direction except by inserting the key either in the cylinder 49 or in the cylinder 33. When the lock is set in this condition even though by means of a small 105 110 115 120 125

opening a person should reach in to the knob 42 it will not be possible to unlock the door.

Having described my invention, what I claim is:

1. A door lock comprising a casing, a bolt therein, a cylinder for said lock arranged whereby the bolt may be operated from outside the door by a key, a hand operated member or knob on said lock accessible only from inside the door for operating the bolt independently of said cylinder, and a cylinder accessible only from inside the door for locking said hand operated member against operation.

2. A door lock comprising a casing, a bolt therein, means accessible from outside the door for operating the bolt with a key, a hand operated bolt throwing means acces-

sible inside the door for operating the bolt 20 and including a member having wings, a sliding member adapted to straddle said wings to prevent the operation of said hand operated means, and a cylinder accessible inside the door by means of which a key will control the operation of said sliding member.

3. A lock comprising a casing having a U shaped, dovetail projection in which a bolt is adapted to slide, a bolt adapted to slide in said projection, a keeper having a dovetail recess adapted to receive said projection when the door is closed, said recess having upper and lower pockets to receive the upper and lower edges of the bolt and means for operating the bolt.

Signed at the city, county and State of New York, this 29th day of August, 1923.

SAMUEL EDELSON.
